(57) **CLAIM**

The ornamental design for an axial piston machine, as shown and described.

DESCRIPTION

FIG. 1 illustrates a perspective view of the axial piston machine showing our new and ornamental design;
FIG. 2 illustrates a front view thereof;
FIG. 3 illustrates a right side view thereof;
FIG. 4 illustrates a rear view thereof;
FIG. 5 illustrates a bottom plan view thereof;
FIG. 6 illustrates a top plan view thereof; and,
FIG. 7 illustrates a left side view thereof.
